UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

RADIO SIGNALING SYSTEM.

Application filed January 20, 1921. Serial No. 438,544.

To all whom it may concern:

Be it known that I, EDWARD W. KELLOGG, a citizen of the United States, residing at Schenectady, in the county of Schenectady, 5 State of New York, have invented certain new and useful Improvements in Radio Signaling Systems, of which the following is a specification.

My present invention relates to radio receiving systems and more particularly to an improved arrangement of an antenna for receiving purposes.

One of the objects of my invention is to provide a receiving antenna which will be 15 an efficient means for receiving radio signals from a desired direction to the substantial exclusion of signals coming from other directions.

In a prior joint application of Chester W. 20 Rice and myself, Serial No. 372,938, filed April 10, 1920, there is described and claimed a receiving antenna having marked unidirectional properties. In this case a 25 long horizontal antenna is employed which extends preferably in the general direction of transmission of the signals to be received and which is preferably of a length of at least the order of magnitude of a half wave 30 length of the signals to be received. In case such an antenna is properly constructed 35 signals coming from a desired station will be found to be strongest at the end of the antenna which is farthest from the transmitting station while signals coming from the opposite direction will be very weak at that 40 end. While for an antenna which is so constructed that the current wave therein will travel along its length at the same velocity as that of the signaling wave in space the 45 signaling current will be strongest at the end farthest from the transmitting station this end may not in all cases be the most favorable point for taking off from the antenna the desired signaling currents. For 50 example, it may be found that at a certain point on the antenna other than the end the ratio of the desired signaling current to undesired currents is more favorable than at any other point. The signaling current 55 may be strongest at a point other than the end of the antenna when the antenna is not in direct line with the transmitting station or when the velocity of current wave 60 on the antenna is not the same as the ve-

locity of the signal waves in space. It may 55 also be found that currents due to undesired disturbances coming from other directions than that of the signal are at a minimum at certain points on the antenna which minimum points will not necessarily 60 fall at the end of the antenna.

The antenna described in the above mentioned application when constructed in its simplest form, namely, a single wire with the receiving circuit located at one end, is 65 a transmission line as well as an antenna. Since it is to function as an antenna it is so constructed as to be sensitive to external influence. Therefore, the relative strength 70 of the desired signaling currents and currents due to undesired influences will vary from point to point. It may not, however, be convenient in all cases to locate the receiving station at the point in the antenna where the relation between the strength of 75 the different currents is most favorable. In some cases therefore it may be desirable to transmit the currents received by the antenna from one place to another without the addition of any new effects from outside 80 sources and without changing the desired relation between the currents.

A second object of my invention is to provide means whereby the receiving station may be located at any desired convenient 85 point along the length of the antenna, and the necessity of locating the receiving station at the point where the relation of the desired signaling currents received to other 90 currents is most favorable will be eliminated. In order to transmit currents from one point to another without bringing in new external influences, a balanced two wire 95 transmission line may be used. If it is desired to transmit the currents from one point on the line of the antenna to another point also on the line of the antenna, the balanced transmission line would normally be located close to or under the antenna. This might 100 be objectionable since the extra wires would be likely to have a disturbing effect on the action of the antenna. Any disadvantage of such an arrangement may be avoided as I have found that by using two wires in multiple as the antenna, the same pair of 105 wires can be made to act as a transmission line.

In attaining the second object of my in-

vention therefore I provide suitable arrangements whereby the antenna itself may be employed as a transmission line for transmitting the signaling currents existing at 5 the selected point to the point where the receiving station is located. I also provide at the receiving station a transformer system which is arranged in such a way that the receiver will not be affected by currents set up 10 in the antenna by waves coming from the opposite direction to that of the signals to be received no matter how strong such currents may be at the receiving station.

While a long horizontal antenna such 15 as that which I employ has decided unidirectional properties, mathematical analysis indicates and experience shows that at the end farthest from the transmitting station small currents will under some conditions 20 be produced by waves coming from the opposite direction even though the end of the antenna nearest the transmitting station is grounded through a resistance approximately equal to the surge impedance of the 25 antenna so that no reflection can occur.

In some cases also it may happen that 30 while the antenna is adjusted so that the receiving apparatus is not affected by disturbing waves coming from a direction exactly opposite to that of the signal, it is affected by disturbances coming from some other direction, for example, 160° from the direction of the transmitting station, and that it is more important to eliminate the effect 35 of disturbing waves coming from this direction than of those coming from a direction 180° from the transmitting station.

Still another object of my invention is to provide means for eliminating the effect 40 upon the receiving station of these small undesired currents produced by waves coming from directions more than 90° from the direction of the transmitting station. Under the conditions mentioned, the surge impedance of the antenna may not be the best impedance to employ in the ground connection of the antenna nearest the transmitting station and therefore in order to attain this object of my invention I provide an 45 impedance which is preferably adjustable in order that the best operating conditions may readily be obtained. This impedance, in order to more nearly eliminate the objectionable effects, may differ from the surge 50 impedance of the antenna either in its resistance or reactive component or in both. One form of impedance which I have found in practice is convenient consists of an adjustable resistance and a series tuned circuit of 55 low impedance. The object of this is to reflect back over the antenna a wave component of the proper magnitude and phase to neutralize the small undesired waves mentioned. By slightly off-tuning this series tuned circuit, a small amount of capacity reactance

or inductive reactance as may be desired may be introduced to give the desired reflection. In other words, by suitable adjustment of the terminal impedance of the antenna it is possible to prevent any undesired reflection and at the same time produce a reflection of the proper nature to eliminate disturbing effects.

The novel features which I believe to be characteristic of my invention are set forth 70 with particularity in the appended claims. My invention itself, however, both as to its organization and method of operation, together with further objects and advantages thereof, will best be understood by reference 75 to the following description taken in connection with the accompanying drawing in which Figs. 1, 2, 3, 4 and 5 show diagrammatically five different arrangements where 80 by my invention may be carried into effect.

As indicated in the drawing, I provide a long horizontal antenna which is preferably made up of at least two parallel wires 1 and 2, the opposite ends of which are 85 grounded at 3 and 4. This antenna is pref- 90 erably so constructed or its constants so

adjusted that the current wave therein will travel along its length at the same velocity as that of the signaling wave in space so that the current wave will gradually grow in amplitude as it travels along the conductor. If it is desired to receive a signal which approaches the antenna from the end 3, the amplitude of the current set up in the antenna at 3 by the desired wave will be extremely small, while at the end 4 the amplitude of the current will be a maximum. It may however be more convenient to locate the receiving station at end 3. In order to permit such a location for the receiving 100 station I employ the antenna conductors as a transmission line for transmitting the desired signaling currents from end 4 to end 3. One convenient way of accomplishing this result is to provide at end 4 a transformer system which may be made up of two similar transformers 5 and 6 as indicated, or the windings of these two transformers may be combined in one transformer if desired. The primary windings 7, 7 of these 105 two transformers are connected in series with the ground connection at 4 and each of the secondary windings 8, 8 have one terminal connected to one of the conductors 1, 2, the other terminal of each transformer being 110 connected to the point 9 at which the ground connection for the antenna is made.

By means of the connections described signaling currents flowing in conductors 1 and 2 toward the end 4 of the antenna flow to 115 ground through the primary windings 7, 7 and are transferred back upon conductors 1 and 2 so as to flow in opposite directions through these two conductors. The conductors 1 and 2 thus form the two sides of a 120

transmission circuit which is closed at the receiving station through the primary windings 10, 10 of a similar pair of transformers 11, 12. The secondary windings 13, 13 of these transformers are connected in series with the receiving apparatus. The signaling currents transmitted from end 4 of the antenna flow through the primary windings 10, 10 in series. Currents received upon the antenna, however, from waves traveling from end 4 toward end 3 flow through the primary windings 10, 10 in parallel to ground and hence produce equal and opposite effects in the secondary windings 13, 13. As a result the receiving apparatus will be unaffected by such currents.

In the case illustrated there is provided in the ground connection an impedance consisting of a variable resistance 14, variable inductance 15, and variable capacity 16. In order to prevent reflection of currents received from ether waves traveling from 4 toward 3 this impedance should be made approximately equal to the surge impedance of the antenna. As has been previously pointed out however, it may in some cases be desirable to produce a certain amount of reflection to neutralize undesired currents produced at end 4 by waves coming from a direction opposite to that of the transmitting station or from a direction at an angle greater than 90° from the direction of the transmitting station. In some cases this desired reflection may be obtained by the use of the resistance 14 alone by making the value of this resistance slightly greater or less than that of the surge impedance of the antenna. In other cases, however, the phase of the component reflected in this way may not be correct for producing the desired neutralization. In such cases, a capacity reactance or an inductive reactance of small amount may be introduced by off-tuning the series tuned circuit made up of inductance 15 and capacity 16, the reactance introduced in this way being sufficient to produce the desired phase in the reflected component.

In Fig. 2 I have indicated an arrangement which may be employed in case it is desired to locate the receiving station at some intermediate point along the length of the antenna. In this case two transformers 17 and 18 are provided having their primary windings inserted in conductors 1 and 2, respectively, and having their secondary windings connected to the receiving apparatus in such a way that currents flowing in opposite directions through the two conductors will add in the receiving apparatus while currents flowing in the same direction will oppose each other. If desired a single transformer of suitable design may be made to perform the function of the two transformers shown. In order that the introduction of a transformer or pair of transformers, in a location

such as shown may not give rise to objectionable reflections, it is generally desirable that it introduce as little impedance as possible into the antenna. To this end I have shown in Fig. 2 a pair of condensers 19 by 70 which the inductive reactance of the transformer windings may be neutralized. If a single transformer is used with close coupling between the two primary windings the reactance to currents flowing in the same 75 direction in the two wires will be low, and this fulfills the condition for avoiding reflections in the antenna.

In Fig. 3 I have indicated an arrangement in which the antenna is utilized as a transmission line as in Figs. 1 and 2, but in which the undesired currents referred to are eliminated in a different manner. In this case a transformer 20 is provided in the ground connection at end 3 by means of which a 80 current of the desired value and phase relation may be impressed upon the receiving apparatus to neutralize the effect of the undesired currents in the receiving apparatus. The magnitude of this current may be adjusted by varying the coupling of transformer 20 and the phase relation may be adjusted by means of the phase rotator indicated.

Fig. 4 shows an arrangement of a transformer or transformers adapted to the case where the ratio of the desired signal current to currents produced by undesired influences is best at a point other than the end of the antenna. The action of the transformer in 95 this case would be the same in principle as the action of a similar transformer when located at the end of the antenna as indicated in Figs. 1 and 2.

Fig. 5 shows still another arrangement of 105 transformers by which currents flowing over the two wires of the antenna in multiple may be made to induce currents which will flow through the two wires in series. To illustrate, when current is flowing from left to right in both of the windings 21, 21, an induced current will flow from right to left in windings 22, 22 and this current flowing through windings 23, 23, will by a second transformation produce a current from right to left in the upper winding 21 of the figure and an equal current from left to right in the lower winding 21. By tuning the circuit comprising the windings 22, 22, 23, 23, the system of transformers shown in Fig. 110 120 5 may be made effective for a particular frequency, and at the same time comparatively ineffective for other frequencies, thus making it possible to perform the transformation at the best point for the reception 115 of a particular signal, while for another signal of different wave length the transformation may be performed at a different point on the antenna.

While I have illustrated and described 125 130

the preferred embodiments of my invention, it will be apparent that my invention is not limited to the particular embodiments indicated, but that many modifications in 5 the particular means whereby my invention may be carried into effect may be made without departing from the scope of my invention as set forth in the appended claims.

One antenna which I have found suitable 10 for carrying out my invention consists of a pair of wires about 14,000 meters long carried by poles approximately 30 feet high. By the use of this antenna I have obtained very satisfactory results in the reception of 15 signals varying in wave length from about 10,000 meters to 23,000 meters and these results have been obtained with the receiving station located at the end of the antenna nearest the transmitting station as well as 20 at intermediate points along the length of the antenna.

What I claim as new and desire to secure by Letters Patent of the United States, is:—

25 1. A receiving system for radio signals comprising a long horizontal receiving antenna and means for utilizing said antenna as a transmission line for conveying signaling currents from a selected point in said 30 antenna where signaling currents received on the antenna from a desired station are strongest to a distant receiving station located along the length of said antenna.

35 2. A receiving system for radio signals comprising a long horizontal receiving antenna comprising a pair of conductors, and means for utilizing said pair of conductors as the two sides of a circuit for conveying signaling currents from a selected point in 40 said antenna to a distant receiving station located along the length of said antenna.

45 3. A receiving system for radio signals comprising a long horizontal receiving antenna and means for utilizing said antenna as a transmission line for conveying signaling currents from the end of said antenna where signaling currents received on the antenna from a desired station are strongest to a distant receiving station located along the 50 length of said antenna.

55 4. A receiving system for radio signals comprising a long horizontal receiving antenna and means for utilizing said antenna as a transmission line for conveying signaling currents from the end of said antenna where signaling currents received on the antenna from a desired station are strongest to a receiving station located at the other end of said antenna.

60 5. A receiving system for radio signals comprising a long horizontal receiving antenna comprising a pair of conductors, and means for utilizing said pair of conductors as the two sides of a circuit for conveying 65 signaling currents from the end of said an-

tenna where signaling currents received on the antenna from a desired station are strongest to a distant receiving station located along the length of said antenna.

6. A receiving system for radio signals 70 comprising a long horizontal receiving antenna comprising a pair of conductors, and means for utilizing said pair of conductors as the two sides of a circuit for conveying signaling currents from the end of said antenna where signaling currents received on the antenna from a desired station are strongest to a receiving station located at the other end of said antenna.

7. A receiving system for radio signals 80 comprising a long horizontal receiving antenna and means for utilizing said antenna as a transmission line for conveying signaling currents from a selected point in said antenna where signaling currents received on the antenna from a desired station are strongest to a distant receiving station located along the length of said antenna, and means for eliminating in the receiving apparatus the effect of currents produced in 85 said antenna at the selected point by waves coming from a different direction from that of the desired signaling waves.

8. A receiving system for radio signals comprising a long horizontal receiving antenna comprising a pair of conductors, ground connections for said antenna at both ends and a transformer system at the end of said antenna where signaling currents from a desired station are strongest, the primary 100 windings of said transformer system being connected in series in the common ground connection for both conductors of the antenna and the secondary windings being connected in series in a circuit which includes 105 the two conductors of the pair in series.

9. A receiving system for radio signals comprising a long horizontal receiving antenna comprising a pair of conductors, ground connections for said antenna at both ends and a transformer system at the end of said antenna where signaling currents from a desired station are strongest, the primary windings of said transformer system being connected in series in the common ground 110 connection for both conductors of the antenna and the secondary windings being connected in series in a circuit which includes the two conductors of the pair in series, the common ground connection being 115 made to an intermediate point in the secondary windings.

10. A receiving system for radio signals comprising a long horizontal receiving antenna comprising a pair of conductors, ground connections for said antenna at both ends and a transformer system at the end of said antenna where signaling currents from a desired station are strongest, the primary 120 windings of said transformer system being 125 connected in series in the common ground connection for both conductors of the antenna and the secondary windings being connected in series in a circuit which includes the two conductors of the pair in series, the common ground connection being 130 made to an intermediate point in the secondary windings.

- connected in series in the common ground connection for both conductors of the antenna and the secondary windings being connected in series in a circuit which includes the two conductors of the pair in series, and a second transformer system at a point distant from the first pair having its primary windings connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.
11. A receiving system for radio signals comprising a long horizontal receiving antenna comprising a pair of conductors, ground connections for said antenna at both ends and a transformer system at the end of said antenna where signaling currents from a desired station are strongest, the primary windings of said transformer system being connected in series in a circuit which includes the two conductors of the pair in series, the common ground connection being made to an intermediate point in the secondary windings, and a second transformer system at a point distant from the first pair having its primary windings connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.
12. A receiving system for radio signals comprising a long horizontal receiving antenna comprising a pair of conductors, ground connections for said antenna at both ends and a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in series, and a second transformer system at the other end of said antenna having its primary windings connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.
13. A receiving system for radio signals comprising a long horizontal receiving antenna comprising a pair of conductors, ground connections for said antenna at both ends and a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in series, and a second transformer system at the other end of said antenna having its primary windings connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.
14. A receiving system for radio signals comprising a long horizontal receiving antenna comprising a pair of conductors, ground connections for said antenna at both ends and a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in series, and a second transformer system at the other end of said antenna having its primary windings connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.
15. A receiving system for radio signals comprising a substantially horizontal receiving antenna which has a ground connection at one end including a resistance substantially equal to the surge impedance of said antenna, and a series tuned circuit in series with said ground connection.
16. A receiving system for radio signals comprising a substantially horizontal receiving antenna which has a ground connection at one end including a resistance substantially equal to the surge impedance of said antenna, and a series tuned circuit of low impedance in series with said ground connection.
17. A receiving system for radio signals comprising a substantially horizontal receiving antenna which is grounded at both ends and a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in series, the common ground connection being made to an intermediate point in the secondary windings, and a second transformer system at the other end of said antenna having its primaries connected in series in said circuit and its secondaries connected to a receiving apparatus in such a way that the receiving apparatus will be influenced by currents flowing in opposite directions along the length of the two conductors but will be unaffected by currents flowing in the same direction in the two conductors.

ends, means at one end of said antenna for preventing any undesired reflection of electric waves traveling along said antenna, and means for producing a desired reflection.

18. A receiving system for radio signals comprising a long horizontal receiving antenna and means for utilizing said antenna as a transmission line for conveying signaling currents from the end of said antenna where signaling currents received on the antenna from a desired station are strongest to a receiving station located at the other end of said antenna, and means at said other end of said antenna for preventing any undesired reflection of electric waves traveling along said antenna and for producing a desired reflection.

19. A receiving system for radio signals comprising a long horizontal receiving antenna and means for utilizing said antenna as a transmission line for conveying signaling currents from a selected point in said antenna to a distant receiving station located along the length of said antenna, and means for eliminating in the receiving apparatus the effect of currents produced in said antenna by waves coming from a different direction from that of the desired signaling waves, said means comprising an arrangement for preventing any undesired reflection of electric waves traveling along said antenna and for producing a desired reflection.

20. A receiving system for radio signals comprising a long horizontal receiving antenna comprising a pair of conductors, ground connections for said antenna at both ends, a transformer system at the end of said antenna where signaling currents from a desired station are strongest, the primary windings of said transformer system being connected in series in the common ground connection for both conductors of the antenna, and the secondary windings being connected in series in a circuit which includes the two conductors of the pair in series, the ground connection at the opposite end of said antenna including means for preventing any undesired reflection of electric waves traveling along said antenna and for producing a desired reflection.

21. A receiving system for radio signals comprising a long horizontal receiving antenna comprising a pair of conductors, ground connections for said antenna at both ends, a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in

series, and a second transformer system at the other end of said antenna having its primaries connected in series in said circuit and its secondaries connected to a receiving apparatus in such a way that the receiving apparatus will be influenced by currents flowing in opposite directions along the length of the two conductors but will be unaffected by currents flowing in the same direction in the two conductors, the ground connection at the receiving station including means for preventing any undesired reflection of electric waves traveling along said antenna and for producing a desired reflection.

22. A receiving system for radio signals comprising a long horizontal receiving antenna comprising a pair of conductors, ground connections for said antenna at both ends, a transformer system at the end of said antenna where signaling currents from a desired station are strongest, the primary windings of said transformer system being connected in series in the common ground connection for both conductors of the antenna and the secondary windings being connected in series in a circuit which includes the two conductors of the pair in series, and a second transformer system at the other end of said antenna having its primary windings connected in series in said circuit and its secondaries connected to a receiving apparatus, the ground connection at the receiving station being made to an intermediate point in the primary windings so that the receiving apparatus will be influenced by currents flowing in opposite directions along the length of the two conductors but will be unaffected by currents flowing in the same direction in the two conductors, and including means for preventing any undesired reflection of electric waves traveling along said antenna and producing a desired reflection.

23. The method of operating a radio receiving system comprising a long horizontal antenna which consists in utilizing the antenna as a transmission line for carrying signaling currents received from a desired station from a selected point in said antenna where such currents have a desired relation to other currents in the antenna to receiving apparatus located at a desired point along the length of said antenna, and at the same time preventing any appreciable change in the desired relation of the currents between the selected point and the point to which the signaling currents are conveyed.

24. The method of operating a radio receiving system comprising a long horizontal antenna which consists in transmitting to the receiving apparatus signaling currents received from a desired station at a selected point in said antenna where such currents

have a desired relation to other currents in the antenna, and eliminating the effect in the receiving apparatus of any undesired current normally flowing at the selected point by producing a reflection over the antenna from another point of a current of equal magnitude and opposite phase to the undesired current.

25. The method of operating a radio receiving system comprising a long horizontal antenna which consists in utilizing the antenna as a transmission line for carrying signaling currents received from a desired station from a selected point in said antenna where such currents have a desired relation to other currents in the antenna to receiving apparatus located a desired point along the length of said antenna, at the same time preventing any appreciable change in the desired relation of the currents between the selected point and the point to which the signaling currents are conveyed, and eliminating the effect in the receiving apparatus of an undesired current normally flowing at the selected point by producing a reflection over the antenna from another point of a current of equal magnitude and opposite phase to the undesired current.

26. The method of operating a radio receiving system comprising a long horizontal antenna which consists in utilizing the antenna as a transmission line for carrying signaling currents received from a desired station from a selected point in said antenna where such currents have a desired relation to other currents in the antenna to receiving apparatus located at a desired point along the length of said antenna, and eliminating the effect in the receiving apparatus of an undesired current normally flowing at the selected point by producing a reflection over the antenna from another point of a current of equal magnitude and opposite phase to the undesired current.

27. A receiving system for radio signals comprising a long horizontal receiving antenna and means for utilizing said antenna as a transmission line for conveying signaling currents from a selected point in said antenna where signaling currents received on the antenna from a desired station have a desired relation to other currents in the antenna to a distant receiving station located along the length of said antenna.

28. A receiving system for radio signals comprising a long horizontal receiving antenna and means for utilizing said antenna as a transmission line for conveying signaling currents from a selected point in said antenna where signaling currents received on the antenna from a desired station have a desired relation to other currents in the antenna, to a distant receiving station located along the length of said antenna, and means for eliminating in the receiving ap-

paratus the effect of currents produced in said antenna at the selected point by waves coming from a different direction from that of the desired signaling waves.

29. A receiving system for radio signals comprising a long horizontal antenna and means for utilizing said antenna as a transmission line for conveying signaling currents from a selected point in said antenna where signaling currents received on the antenna from a desired station have a desired relation to other currents in the antenna to a distant receiving station located along the length of said antenna, and means for eliminating in the receiving apparatus the effect of currents produced in said antenna by waves coming from a different direction from that of the desired signaling waves, said means comprising an arrangement for preventing any undesired reflection of electric waves traveling along said antenna and for producing a desired reflection.

30. The method of eliminating the effect in a long horizontal receiving antenna of undesired currents at a selected point where signaling currents received from a desired station have a desired relation to other currents in the antenna which consists in producing a reflection over the antenna from another point of a current of equal magnitude and opposite phase to the undesired current.

31. A receiving system for radio signals comprising a long horizontal receiving antenna and means for utilizing said antenna as a transmission line for conveying signaling currents from a selected point in said antenna where signaling currents received on the antenna from a desired station have a desired relation to other currents in the antenna to a distant receiving station located along the length of said antenna, and means for preventing any appreciable change in the desired relation of the currents between the selected point and the point to which the signaling currents are conveyed.

32. A receiving system for radio signals comprising a long horizontal receiving antenna and means for utilizing said antenna as a transmission line for conveying signaling currents from a selected point in said antenna where signaling currents received on the antenna from a desired station have a desired relation to other currents in the antenna, to a distant receiving station located along the length of said antenna, means for eliminating in the receiving apparatus the effect of currents produced in said antenna at the selected point by waves coming from a different direction from that of the desired signaling waves, and means for preventing any appreciable change in the desired relation of the currents between the selected point and the point to which the signaling currents are conveyed.

33. A receiving system for radio signals comprising a long horizontal receiving antenna and means for utilizing said antenna as a transmission line for conveying signaling currents from a selected point in said antenna where signaling currents received on the antenna from a desired station have a desired relation to other currents in the antenna to a distant receiving station located along the length of said antenna, means for eliminating in the receiving apparatus the effect of currents produced in said antenna by waves coming from a different direction from that of the desired signaling waves, said means comprising an arrangement for preventing any undesired reflection of electric waves traveling along said antenna and for producing a desired reflection, and means for preventing any appreciable change in the desired relation of the currents between the selected point and the point to which the signaling currents are conveyed.

34. A receiving system for radio signals comprising a long horizontal receiving antenna and means for utilizing said antenna as a transmission line for conveying currents produced in said antenna from a selected point where the currents transmitted have desired characteristics for use in a receiving apparatus to a distant receiving station located along the length of the antenna.

35. A receiving system for radio signals comprising a long horizontal receiving antenna comprising a pair of conductors, and means for utilizing said pair of conductors as the two sides of a circuit for conveying currents produced in said antenna from a selected point in said antenna to a distant receiving station located along the length of said antenna.

36. A receiving system for radio signals comprising a long horizontal receiving antenna and means for utilizing said antenna as a transmission line for conveying currents produced in said antenna at one end where the currents transmitted have desired characteristics for use in a receiving apparatus to a distant receiving station located along the length of the antenna.

37. A receiving system for radio signals comprising a long horizontal receiving antenna and means for utilizing said antenna as a transmission line for conveying currents produced in said antenna at one end where the currents transmitted have desired characteristics for use in a receiving apparatus to a distant receiving station located at the other end of said antenna.

38. A receiving system for radio signals comprising a long horizontal receiving antenna comprising a pair of conductors, and means for utilizing said pair of conductors as the two sides of a circuit for conveying currents produced in said antenna at one end where the currents transmitted have de-

sired characteristics for use in a receiving apparatus to a distant receiving station located along the length of the antenna.

39. A receiving system for radio signals comprising a long horizontal receiving antenna comprising a pair of conductors, and means for utilizing said pair of conductors as the two sides of a circuit for conveying currents produced in said antenna at one end where the currents transmitted have desired characteristics for use in a receiving apparatus to a distant receiving station located at the other end of said antenna.

40. A receiving system for radio signals comprising a long horizontal receiving antenna comprising a pair of conductors, ground connections for said antenna at both ends and a transformer system at one end of said antenna, the primary windings of said transformer system being connected in series in the common ground connection for both conductors of the antenna and the secondary windings being connected in series in a circuit which includes the conductors of the pair in series.

41. A receiving system for radio signals comprising a long horizontal receiving antenna comprising a pair of conductors, ground connections for said antenna at both ends and a transformer system at one end of said antenna, the primary windings of said transformer system being connected in series in the common ground connection for both conductors of the antenna and the secondary windings being connected in series in a circuit which includes the two conductors of the pair in series, the common ground connection being made to an intermediate point in the secondary windings.

42. A receiving system for radio signals comprising a long horizontal receiving antenna comprising a pair of conductors, ground connections for said antenna at both ends and a transformer system at one end of said antenna, the primary windings of said transformer system being connected in series in the common ground connection for both conductors of the antenna and the secondary windings being connected in series in a circuit which includes the conductors of the pair in series, and a second transformer system at a point distant from the first transformer system having its primary windings connected in series in said circuit and its secondary windings connected to a receiving apparatus in such a way as to impress thereon currents flowing in opposite directions along the length of the two conductors without impressing thereon currents flowing in the same direction in the two conductors.

43. A receiving system for radio signals comprising a long horizontal receiving antenna comprising a pair of conductors, ground connections for said antenna at both

ends and a transformer system at one end of said antenna, the primary windings of said transformer system being connected in series in the common ground connection for both conductors of the antenna and the secondary windings being connected in series in a circuit which includes the conductors of the pair in series, and a second transformer system at the other end of said antenna having its primary windings connected in series in said circuit and its secondary windings connected to a receiving apparatus in such a way as to impress thereon currents flowing in opposite directions along the length of the two conductors without impressing thereon currents flowing in the same direction in the two conductors. 15

In witness whereof, I have hereunto set my hand this 18th day of Jany., 1921.

EDWARD W. KELLOGG.
